(57) **CLAIM**

The ornamental design for a dispenser, as shown and described.

DESCRIPTION

FIG. 1 is a perspective view of my dispenser, with the top closed.

FIG. 2 is a front elevational view of my dispenser.

FIG. 3 is a rear elevational view of my dispenser.

FIG. 4 is a right side elevational view of my dispenser.

FIG. 5 is a left side elevational view of my dispenser

FIG. 6 is a top plan view of my dispenser

FIG. 7 is a bottom plan view of my dispenser; and,

FIG. 8 is a perspective view of my dispenser, with the top open.

The broken-line disclosure in the views is for illustrative purposes only and forms no part of the claimed design.
